UNITED STATES PATENT OFFICE.

CHARLES W. DAVIS, OF EDGEWORTH, PENNSYLVANIA, ASSIGNOR TO STANDARD UNDERGROUND CABLE COMPANY, OF PITTSBURGH, PENNSYLVANIA, A CORPORATION OF PENNSYLVANIA.

ELECTRIC FUSE.

1,130,484.

Specification of Letters Patent.

Patented Mar. 2, 1915.

Application filed April 22, 1913. Serial No. 762,889.

To all whom it may concern:

Be it known that I, CHARLES W. DAVIS, residing at Edgeworth, in the county of Allegheny and State of Pennsylvania, a citizen of the United States, have invented or discovered certain new and useful Improvements in Electric Fuses, of which improvement the following is a specification.

My invention relates to electric fuses, and 10 particularly to those adapted to be used in connection with high voltage currents.

The blowing of an electric fuse takes place, as is well known, when the current carried thereby becomes abnormal and dangerous. In addition to this increase in current strength necessary in order to blow the fuse, there is a very rapid rise in the current immediately after such blowing and until the arc is finally broken.

20 It is the object of my invention to render this double increase in electric currents effective to widen the gap between the adjacent ends of the ruptured or blown fuse strip, there being little if any strain upon 25 the strip up to the time of its blowing. To such an end I provide an electro-magnet in circuit with the fuse strip, and I provide an operative connection between a movable part of such magnet and an end of the fuse strip, 30 the arrangement being such that the magnet exerts a relatively small strain upon the fuse strip while a normal current is passing through it, but is effective to quickly widen the gap in the fuse strip upon the blowing 35 thereof.

In the accompanying drawing, which forms part of my specification, I have illustrated in a single figure one embodiment of my invention.

40 The figure is a vertical sectional view of a junction box, showing two cables entering therein, the fuse structure connecting the cables being shown partly in elevation and partly in vertical section.

45 The two cables 1, which enter the junction box 2, are each provided with a terminal structure 3, comprising, in part, a spring clip 4, electrically connected to the conductor core of the cables. The fuse structure is 50 movably secured to said spring clips, and comprises a frame 5 of insulating material; conducting brackets 6 and 7, secured to the opposite ends of said frame; coil 8 and fuse

casing 9, secured to said brackets 6 and 7, respectively; and a movable core 10. Each of 55 said brackets is provided with a collar 11, and with a knife-blade contact 12 adapted to be engaged by the spring clips 4. The coil 8 is mounted within the collar 11 of bracket 6, and is wound by a continuation of the conductor 13, electrically connected to said bracket; while fuse casing 9 is mounted within the collar 11 of bracket 7, the fuse strip 14 extending through such casing. The outer end of the casing 9 is closed by 60 means of a removable plug 19 provided with a contact cap 20 to which the fuse strip 14 is electrically connected, and which in turn is adapted to be engaged by the spring arms 21 secured to the collar 11 of bracket 7. 70

The path of electrical conductivity between the fuse strip 14 and the bracket 6 is preferably effected through the core 10. To such an end said core comprises a sleeve of conducting material 15, and a stranded iron 75 core 16, the outer end of said sleeve being electrically connected to the fuse strip 14 by means of a stem 17 extending loosely through an opening in the end of the casing 9, and the inner end of said sleeve being 80 electrically connected to the coil 8 by means of a flexible conductor 18. In order to prevent a material strain upon the fuse strip 14 during such time as it is carrying a normal current the stranded iron core 16 of the 85 electro-magnet preferably extends but to the end of the coil 8, as will be seen by the termination of the dotted lines at the end of the coil.

As will be readily seen, the several current-carrying conductors are arranged in 90 series, so that a current, in passing from the bracket 6 to the bracket 7, flows through the conductor 13, coil 8, flexible conductor 18, core sleeve 15, stem 17, fuse strip 14, cap 95 20 and spring arms 21. While, during the passing of a normal current through such conductors, there will of course be a small stress upon the fuse strip 14, the electro-magnet is so proportioned that such stress 100 will have no prejudicial effect, but further is so proportioned that the increased current, encountered at the time of the blowing of the fuse, will quickly move the core 10, thereby widening the gap between the ends 105 of the ruptured fuse. In the drawing I

have indicated in dotted lines the position of the core 10 and the flexible conductor 18 after such core has been drawn within the coil.

5 While my invention may be effectively employed in various electrical installations, the particular form illustrated herein is well adapted for use in a junction box filled with an arc-dampening fluid.

10 I claim as my invention:

1. In an electric fuse, the combination of a fuse strip, an electro-magnet comprising a coil and a core movable with relation to each other, said coil being in circuit with 15 said strip and having its several convolutions immovable with relation to each other in the operation of the fuse, and means for connecting the movable member of the magnet to said strip for exerting a tension thereon, said movable member becoming effective to widen the gap between the adjacent free ends of said strip when blown.

2. In an electric fuse, the combination of a fuse strip, an electro-magnet having a 25 movable core secured to one end of said strip, and the coil of said magnet being in circuit with said strip and adapted to receive said core upon the blowing of said strip, the several convolutions of said coil

in the operation of the fuse being immovable with relation to each other.

3. In an electric fuse, the combination of a fuse strip, an electro-magnet having a coil in circuit with said strip, and the core of said magnet being electrically and structurally connected at its opposite ends to said coil and to an end of said strip, the several convolutions of said coil in the operation of the fuse being immovable with relation to each other.

4. In an electric fuse, the combination of a frame, a pair of terminal contacts secured to said frame, a casing borne by one of said terminal contacts, a fuse strip within said casing and secured thereto at one end, an electro-magnet having its coil secured to the other of said terminal contacts, the core of said magnet being secured to one end of said fuse strip and movable through said coil, said fuse strip, coil and contact terminals being in a series circuit.

In testimony whereof I have hereunto set my hand.

CHARLES W. DAVIS.
